(57) **CLAIM**

The ornamental design for a floor panel for a clean room, as shown and described.

DESCRIPTION

FIG. 1 is a perspective view of a floor panel for a clean room showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof;

FIG. 8 is a rear perspective view indicating a partial view labeled 9; and,

FIG. 9 is an enlarged rear perspective view of area 9 in FIG. 8.

The broken lines are for illustrative purposes only and form no part of the claimed design.
